US00D959253S

(12) **United States Design Patent** (10) **Patent No.:** **US D959,253 S**
(45) **Date of Patent:** **** Aug. 2, 2022**

(54) **ADJUSTABLE CLAMP DEVICE**

(71) Applicant: **Shaw P. Wan**, Norwood, NC (US)

(72) Inventor: **Shaw P. Wan**, Norwood, NC (US)

(73) Assignee: **Well Lead Co, LTD**, Guangzhou (CN)

(**) Term: **15 Years**

(21) Appl. No.: **29/754,172**

(22) Filed: **Oct. 7, 2020**

(51) LOC (13) Cl. **08-08**

(52) U.S. Cl.

USPC **D8/394**; D8/72

(58) **Field of Classification Search**

USPC D8/349, 352, 382, 72, 394, 395, 396, 73,

(57) **CLAIM**

The ornamental design for a adjustable clamp device, as shown and described.

DESCRIPTION

FIG. 1 is a perspective view of the top of the adjustable clamp.

FIG. 2 is a perspective view of the top of the adjustable clamp.

FIG. 3 is a perspective view of the bottom of the adjustable clamp.

FIG. 4 is a side view of the adjustable clamp.

FIG. 5 is a top view of the adjustable clamp.

FIG. 6 is a bottom view of the adjustable clamp.

FIG. 7 is a side view of the adjustable clamp; and,

FIG. 8 is a side view of the adjustable clamp.

1 Claim, 6 Drawing Sheets
